UNITED STATES PATENT OFFICE.

FRANZ LAWACZEK, OF MUNICH, GERMANY, ASSIGNOR TO WORTHINGTON PUMP AND MACHINERY CORPORATION, OF NEW YORK, N. Y., A CORPORATION OF VIRGINIA.

COMPRESSOR OR VACUUM AIR PUMP.

Application filed August 17, 1926. Serial No. 129,679.

The present invention relates to air or gas compressors, vacuum air pumps and the like, of the kind in which a rotary wheel or runner fitted with blades is traversed by a number 5 of water jets which force before themselves in the manner of a piston, and compress, the air or gas which occupies the blading-passages of the runner between the several water-jets. In such air pumps or compressors with 10 multiple partial admission the maintenance of air-tightness between the air suction chamber and the pressure chamber occasions difficulties, for the danger arises—and this increases with the difference of pressure between 15 pressure and suction chambers and is therefore especially great in the case of vacuum pumps—that the air may rush back from the pressure chamber into the suction chamber, and consequently, in the case of vacuum 20 air pumps, may destroy the vacuum. The outlet end of those cells of the partial-admission runner the inlets of which open towards the air-admission chambers must therefore remain with certainty blocked with respect to 25 the pressure chamber until the inlet end of the blading-cells is shut off from the air suction chamber by the entering water.

To this end, according to the present invention, the direction of the jet of water 30 which penetrates the runner has such an inclination to the direction of the blading-passages of the runner that this jet of water blocks the blading-cells in relating to the pressure chamber until the adjacent water-jet 35 traversing the runner closes the inlet portion of the cell occupied by the air to be compressed. Moreover, in order with more certainty to block the said cells exposed to the pressure chamber, according to the present 40 invention, it is preferred that the outlet end of the blading-passages of the runner between the water-outlet port and the adjacent compressed air port be in part covered in such manner that there still remains in 45 the blading-cells a layer of water held by centrifugal force, which serves as packing or closure means between the pressure and suction (or vacuum) chambers. The volume of water which, in this case, possibly reaches the 50 pressure chamber can conveniently be separated in any desired manner from the compressed air or the like.

One of the numerous possible embodiments of the present invention is shown by way of

example in the accompanying drawings, 55 wherein

Fig. 1 is a radial section of a hydraulic air pump, the sectional plane being taken at right angles to the rotary axis of the pump and being indicated by the line A—B in Fig. 60 2, and

Fig. 2 is a vertical section, the sectional plane including said axis and being indicated by the line C—D in Fig. 1.

Referring to the drawings, the casing 1 65 carries in its interior the two bearings 2, 3 of the shaft 4 on which is keyed a runner 5 which carries by means of spokes a bladed wheel 6 provided with inclined blades 7 which form cellular chambers 8.

Axially arranged with respect to the shaft 4, there are provided on the casing the pipe-connections 9 and 10, of which the former 9 serves for introducing water under pressure and the latter 10 for the inlet of the air or 75 gas to be compressed. The annular passage 11 adjoining the pipe connection 9 is divided into a number of ports or nozzles—in the example shown, into four of the same—which have such an inclination that the jet of water 80 issuing from them is inclined in the opposite direction to the blades 7 of the runner, so that each of the four jets of water flows outwardly through the runner 5 about at right angles to the blades 7. In the example shown, the 85 runner is itself rotated by these jets of water issuing from the nozzles 12. The said runner may however be driven externally, although such an arrangement is less advantageous 90 since a packing gland must then be provided on the casing 1 of the machine at the place where the driving shaft emerges. The embodiment shown, on the other hand, requires no packing gland whatever, the avoidance 95 of which is of special importance in the event its being possible for the outside air to penetrate through it into the vacuum of a condenser to which the machine may be connected.

The pipe-connection 10 for introducing the 100 air to be compressed is connected, through the spokes of the wheel 5, to the intermediate chambers 13 between the water-jet nozzles 12. Each water-jet 14, which widens outwardly in accordance with its reduction of energy, not 105 only in the radial plane of Fig. 1, but, owing to the corresponding widening of the blading-chambers 8 preferably also in the axial plane

of Fig. 2 at right angles to the former plane, is for the greater part caught when it issues from the outer periphery of the blading-passages 8 by the ports 15 which, by being 5 suitably curved, all unite in the water-outlet pipe-connection 17.

Located between the ports 15 at the outer periphery of the blading-passages 8 of the runner are provided ports 16 for the compressed air, which are connected to ducts uniting in the compressed-air pipe-connection 20.

The mode of operation of the machine is as follows:—

The pressure-water which enters through 15 the pipe-connection 9 and the annular duct 11, and is divided by the nozzle 12 into four jets, sets the runner 5 in rotation. Each water-jet 14 thereby roughly takes the form shown in Fig. 1 in flowing outwardly through 20 the blading-passages 7, 8 of the runner. The blades 7 therefore cut through each water-jet which at times fills only a portion of the cell-chamber 8. After crossing the water-jet 14 the inner or suction end of the cell 8 becomes 25 connected with the air-suction chamber 13 located between two jets, so that each cell 8, to the extent to which it passes out of the jets 14, becomes occupied by or charged with the air or the like to be compressed. On further 30 rotation, the inner or suction end of the cell 8 enters the water-jet 14 next following which cuts off the cell from the air-suction chamber. On still further rotation of the wheel, this water-jet compresses the air present 35 in the cell 8 and removes it uniformly from the interior of the cell 8 into the compressed-air chamber 16.

In order to guarantee that in any case no connection can occur between the compressed-air chamber 16 and the suction chamber 13, in accordance with the present invention, the water-jets 14, on the one hand, and the oppositely directed blades 7, on the other hand, are so inclined to one another that each water-jet 14 blocks the blading-cells 8 in relation to the compressed-air chamber 16 until the next-following water-jet 14 to be crossed by the cells during the rotation of the wheel 5 blocks that inlet portion of the cell 8 which is situated at 40 the inner periphery of the runner. It will be observed for example, respecting the runner-cells 8¹ of Fig. 1 that the end of a cell located at the outer periphery of the runner 5 is still closed by the portion 14¹ of the water-jet 14 just crossed, while the portion 14² of the water-jet now to be crossed has already closed the inner or suction end of the cell 8¹ by the air in the middle of the cell's length being shut in by water on both sides.

It is recommended to maintain as long as possible the closure of each cell at its outlet end. To this end, there is connected, to that wall of each nozzle 15 which receives the water jet 14 traversing the runner, a further 55 wall-element 18 which somewhat screens the

outlet end of the runner-cell 8 from the compressed air chamber. A portion of the issuing jet of water 14 is pressed by centrifugal force against this covering wall 18 and in this way closes the outlet end of the cells 8 themselves if a high vacuum in the air suction chamber 13 should tend to draw this water inwards. The small mass of water 19 which in this case possibly reaches the compressed air chamber can be separated in any desired 75 manner from the compressed air or the like.

I claim:—

1. An air pump of the kind described, comprising a runner having a plurality of blades which form inclined blading-cells, and a casing having air and pressure-water inlets and outlets coacting with said runner, a water-inlet and a water-outlet for directing each jet of water between front and rear air-inlets and front and rear air-outlets, and for giving to said jet such an inclination to the blading-cells that the cells connecting a front inner air-inlet with a rear air-outlet are blocked by said jets, while the cell immediately in front of said cells is blocked not only by said jet but also by the jet in advance.

2. An air pump of the kind described, comprising a runner having a plurality of blades which form inclined blading-cells, and a casing having air and pressure-water inlets and outlets coacting with said runner, a water inlet and a water-outlet for directing each jet of water between front and rear air-inlets and front and rear air-outlets, and for giving to said jet such an inclination to the blading-cells that the cells connecting a front inner air-inlet with a rear air-outlet are blocked by said jets, while the cell immediately in front of said cells is blocked not only by said jet but also by the jet in advance, said casing also having a circumferential wall covering the blading-cells located between each water-outlet and the air-outlet immediately in advance of the same.

3. An air pump of the kind described, comprising a runner having a plurality of blades which form inclined blading-cells, and a casing having air and pressure-water inlets and outlets coacting with said runner, a water-inlet and a water-outlet for directing each jet of water between front and rear air-inlets and front and rear air-outlets, and for giving to said jet such an inclination to the blading-cells that the cells connecting a front inner air-inlet with a rear air-outlet are blocked by said jets, while the cell immediately in front of said cells is blocked not only by said jet but also by the jet in advance, the first-named jet of water being inclined in the opposite direction to the blades of the runner.

4. An air pump of the kind described, comprising a runner having a plurality of blades which form inclined blading-cells, and a casing having air and pressure-water inlets and outlets coacting with said runner, a water

- inlet and a water-outlet for directing each jet of water between front and rear air-inlets and front and rear air-outlets, and for giving to said jet such an inclination to the blading-
 5 cells that the cells connecting a front inner air-inlet with a rear air-outlet are blocked by said jets, while the cell immediately in front of said cells is blocked not only by said jet but also by the jet in advance, said
 10 casing also having a circumferential wall covering the blading-cells located between each water-outlet and the air-outlet immediately in advance of the same, the first-named jet of water being inclined in the opposite
 15 direction to the blades of the runner.
5. A pump comprising a casing having separate delivery ports for air and water, a bladed wheel rotatable in said casing, supply means cooperating with one edge of said
 20 wheel for the supply of alternating plugs of water and air thereto, and a plurality of separate water and air discharge ports cooperating with the opposite edge of said wheel for the separate delivery of the air and water
 25 to said casing.
6. A pump comprising a casing having separate delivery ports for air and water, a bladed wheel rotatable in said casing, alternating water and air inlets cooperating with
 30 one edge of said wheel for the supply of alternating plugs of water and air thereto, a plurality of alternating water and air discharge ports cooperating with the opposite edge of said wheel for the separate delivery
 35 of the air and water to said casing.
7. A pump comprising a casing having separate delivery ports for air and water, a bladed wheel rotatable in said casing, alternating water and air inlets cooperating with
 40 the inner periphery of said wheel for the supply of alternating plugs of water and air thereto, and a plurality of separate water and air discharge ports cooperating with the outer periphery of said wheel for the sepa-
 rate delivery of the air and water to said cas- 45
 ing.
8. A pump comprising a casing having separate delivery ports for air and water, a bladed wheel rotatable in said casing, alternating water and air inlets cooperating with
 50 the inner periphery of said wheel, a plurality of separate water and air discharge ports cooperating with the outer periphery of said wheel for the separate delivery of the air and water to said casing, and means between said
 55 water and air outlets to retain a small portion of water in said wheel under centrifugal force.
9. A pump comprising a casing having separate delivery ports for air and water, a wheel having inclined blades rotatable in said casing, a plurality of nozzles supplying water under pressure to the inner periphery
 60 of said wheel and inclined oppositely to the inclination of said blades, an air supply passage connecting with the spaces formed between said water supply nozzles, and a plurality of separate water and air discharge ports
 65 cooperating with the outer periphery of said wheel for the separate delivery of the air and water to said casing.
10. A pump comprising a casing having separate delivery ports for air and water, a wheel having inclined blades rotatable in said casing, a plurality of nozzles supplying water
 70 under pressure to the inner periphery of said wheel and inclined oppositely to the inclination of said blades, an air supply passage connecting with the spaces formed between said water supply nozzles, a plurality of separate
 75 water and air discharge ports cooperating with the outer periphery of said wheel for the separate delivery of the air and water to said casing, and means between said water and air outlets to retain a small portion of water
 80 in said wheel under centrifugal force.
